UNITED STATES PATENT OFFICE.

GERALD E. TURNER, OF LYNN, MASSACHUSETTS, ASSIGNOR TO A. E. LITTLE COMPANY, OF LYNN, MASSACHUSETTS, A CORPORATION OF MASSACHUSETTS.

GAUGE FOR BOOT AND SHOE MACHINES.

Application filed February 14, 1921. Serial No. 444,714.

To all whom it may concern:

Be it known that I, GERALD E. TURNER, a citizen of the United States, residing at Lynn, county of Essex, Commonwealth of

Massachusetts, have invented a certain new and useful Improvement in Gauges for Boot and Shoe Machines, of which the following is a specification, reference being had therein to the accompanying drawings.

10 My invention relates to a gauge for use on boot and shoe machines. While the gauge embodying my invention is capable of use on a variety of machines which perform operations along the edge of the sole, I have 15 shown my invention in the accompanying drawings as forming part of a heel nailing machine or so-called "loose nailer" because I have put the invention into actual practice in connection with machines of this 20 type. I do not, however, intend to limit myself to use in this combination, as it will be obvious that it is capable of successful use in connection with machines that perform other operations on boots and shoes, as for 25 instance, stitching, rough-rounding, and the like.

Heretofore great difficulty has been experienced with loose nailing machines with these gauges commonly called "counter gauges," owing to the fact that it is necessary to set the gauge in position to place the nails correctly at the back of the shoe. This is necessary because the shoe is shaved off there at the greatest angle to conform to the shape of the heel at this point. The gauge therefore has to be set back a considerable distance from the counter at this point with the result that when the sides of the shoe are presented to the machine, the nails 40 will be set too far in from the edge of the sole and it is found that when the nailing is completed, the nails forms a V-shaped figure and not a U-shaped figure the line of which follows around the edge of the sole at a substantially uniform distance from it. This 45 is a serious defect in the shoe, because the counter is secured to the outsole only at the extreme inside edge of the inturned flange of the counter, thus permitting the crease between the counter and the outsole to open. Furthermore, with the old-fashioned counter 50 gauge, a high degree of skill is required of the workmen since the shoe contacts with the

gauge at one point only. Incorrect presentation of the shoe to the machine is therefore easily possible and can be prevented only by the skill of the operator.

In the gauge embodying my invention, I provide a pair of contact members which are preferably but not necessarily in the form 55 of freely rotatable disks, the edges of which are adapted to enter the crease between the outsole and the upper, said disks being mounted on opposite sides of a line which is normal to the edge of the shoe and which passes through the point of operation of the working instrumentalities of the machine. The shoe, therefore, contacts with the gauge at two quite widely separated 60 points instead of one point as heretofore 65 and, therefore, its position with relation to the working instrumentalities of the machine is fixed and not dependent upon the skill of the operator. In other words, the work is accurately guided during its passage by the 70 working instrumentalities and not merely limited as to its movement with respect thereto in one direction. On the side of the 75 shoe where the crease is practically straight, the point of operation of the working instrumentalities will be brought relatively 80 close to the edge of the shoe while at the heel where the crease of the shoe is curved sharply in plan view, the point of operation of the working instrumentalities will be further 85 from the edge of the shoe since the shoe is permitted by the curvature of the heel portion to enter the space between the two disks. To improve the operation still further and 90 prevent the operator from forcing the shoe 95 away, the support on which the disks are mounted is pivoted on an axis parallel to the axes of rotation of the disks and consequently perpendicular to the plane in which the work is guided, thus permitting the bodily angular displacement of the gauge in said 100 plane, said displacement being limited by means which will be described.

This arrangement makes the work of feeding the shoe to the nailing mechanism easier 100 and one which requires less skill and strength on the part of the operator. By this arrangement it is easier for the operator to keep the shoe in contact with both wheels instead of allowing the shoe to ride on one 105 wheel as is likely to occur without the

knowledge of the operator, especially on large shoes if the mounting for the gauge is fixed.

I find in actual practice that a gauge embodying my invention is much more satisfactory than the gauges heretofore employed, and that when employed on a loose nailer, the nails will be set in a U-shape at a good distance from the inside edges of the in-turned flanges of the counter and at substantially uniform distance from the edge of the insole, thereby producing a much stronger and more durable shoe than heretofore. The gauge embodying my invention is not substantially more expensive than the gauge as heretofore constructed.

The invention will be fully understood from the following description when taken in connection with the accompanying drawings, and the novel features thereof will be pointed out and clearly defined in the claims at the close of this specification.

In the drawings, Fig. 1 is a front elevation of a loose nailer to which is applied the gauge embodying my invention.

Fig. 2 is a side elevation of the gauge, a portion of a shoe being shown in connection therewith.

Figs. 3, 4, 5 and 6 are top plan views of the gauge showing four successive positions of the parts in nailing around the heel of the shoe.

Referring now to the drawings, at 11 is shown the guard plate, at 12 the throat, at 13 the awl, at 14 the awl bar, at 15 the driver and at 16 the driver guide of a loose nailer of ordinary construction. These parts being old and well known and forming no part of my invention will not be described in detail.

At 17 is shown a bracket on the underside of the guard plate 11. To this bracket is pivoted at 18 the counter gauge arm 19 having a tail *a* which extends rearwardly. Through a hole in this tail passes a stud 20 secured to the underside of the guard plate 11, there being a spring 21 between the guard plate and the tail of the counter gauge arm. The tension on the spring is adjustable by means of a thumb nut 22. The forward extending end of the arm is provided with a substantially vertical pivot 23 to which is secured the support 24. The rear end of the support is forked, as shown at *b* and *c* in Figure 3, the prongs of the fork being downwardly extended on opposite sides of the counter gauge arm 19. This permits the support 24 to swing slightly about the pivot 23, but the range of movement is limited by the prongs of the fork which strike the sides of the counter gauge arm 19. On the front end of the support 24 are pivoted at 27 and 28 two freely rotatable gauge members 25 and 26 which, in the form shown in the drawings, are conveniently hard fibre wheels having edges *m* of a shape adapted to enter

the crease between the upper *d* and outsole *e* of a shoe, a portion of which is shown in the drawings. In operating the machine, the shoe to be operated upon being then upon the last, is held against the gauge with both contact members in the crease between the upper and outsole. The points of contact of the contact members with the edge of the sole will therefore be seen to be on opposite sides and equi-distant from the line *f*—*g* which passes through the point of operation *h* of the working instrumentalities upon the shoe and is normal to the edge of the shoe, said line, in the construction shown, also passing through the axis of the pivot 23. The distance of the point of operation *h* shown in the drawings as a nail head is dependent upon the curvature of the portion of the edge of the shoe lying between the two contact wheels, thus where the edge is practically straight, as shown in Figure 3, it will be nearer the edge of the shoe than in the position shown in Figure 5 at the heel of the shoe where the curvature of the heel is considerable and enters the space between the contact members 25 and 26.

The support 24 also swings slightly about the pivot 23, the movement being as great as is permitted by the fork at the rear end, and being substantially in, or parallel to, the plane in which the work is guided. Thus, in the construction shown, the work is guided for approximately horizontal movement, and the axis of the pivot is approximately vertical, or substantially perpendicular to the plane of movement of the work, so that the swinging movement of the support is also approximately horizontal. This movement permits the gauge to adjust itself bodily and as a unit as the work progresses around the edge of the sole, keeping the work against both disks and preventing the use of one disk alone. When the work is in the position shown in Figure 3, the support will be in about midposition. As the heel is reached (see Figure 4) the support swings to the position shown, the prong *b* of the fork being in contact with the side of the arm 19. As the other corner of the heel is reached, the work support swings in the other position (see Figure 5) and again resumes its mid-position when the other side of the shoe is reached.

It will be seen that the gauge or guide as a whole is substantially fixed against lateral movement, or movement in the direction in which the work is presented to the machine, and that, the pivot 23 being located between the work engaging members and closely adjacent thereto, an inward movement of one of said members is accompanied by a substantially equal outward movement of the other, so that while the limited swinging movement of the guide permits the edge of the work to be presented at somewhat vary-

ing angles, its distance from the working instrumentalities, as determined by its curvature, is not materially affected.

The gauge embodying my invention makes the work of presenting the shoe properly to the working instrumentalities practically automatic, since the gauge contacts with the line of curvature of the edge of the shoe at two points and thus guides the movement of the shoe and determines the position thereof in each of the successive positions which the shoe takes during the operation. With the old-fashioned gauge which contacted with the shoe at one point only, the position of the shoe was not fixed by the gauge but by the operator, and therefore if allowed to slip as frequently done, defective work resulted. The difference in operation between these two gauges will perhaps be more clearly understood when the principle of geometry is remembered that the position of a line cannot be fixed by a single point but only by two points.

What I claim is:—

1. A fixed work guide for boot and shoe machines comprising two disks mounted to rotate freely upon spaced parallel axes and to be freely movable as a unit in a plane substantially perpendicular to said axes. 25

2. A work guide for boot and shoe machines comprising two disks, a movable support on which said disks are mounted to rotate freely upon spaced parallel axes, and a fixed support on which said movable support is mounted to have a limited movement 30 35 as a unit about a third axis substantially parallel to said first named axes.

3. The improved gauge for boot and shoe machines comprising a support, two freely rotatable disks mounted on said support, a 40 mounting for said support on which the support is pivoted to swing in a plane at right angles to the axes of rotation of the disks and means for limiting the movement of the support on said pivot. 45

In testimony whereof I affix my signature.

GERALD E. TURNER.
